UNITED STATES PATENT OFFICE

MARIO GRIMALDI, OF ROME, ITALY.

BLADE FOR RAILWAY-SWITCHES.

1,088,567.

Specification of Letters Patent.

Patented Feb. 24, 1914.

Application filed April 5, 1912. Serial No. 688,608.

To all whom it may concern:

Be it known that I, MARIO GRIMALDI, a subject of the King of Italy, mechanician, and a resident of Rome, in the Kingdom of Italy, have invented certain new and useful Improvements in Blades for Railway-Switches, of which the following is a full, clear, and complete specification.

The invention refers to a blade for railway switches and consists substantially in that the heel of the blade is revoluble around a pivot which is carried by a support movable upon a slide plate.

In the drawing Figure 1 shows the plan view of a switch permanently set on the branch line. Fig. 2 is a plan view of a switch, in which the blade is set on the straight line. Figs. 3 and 4 are vertical sections on enlarged scale according to the lines A—B and C—D of Fig. 1.

The main line is represented by the rail —1— and the branch line by the rail —2—. The point 4 of the blade 3 by means of the pivot —19— is linked to the joint —5—, to which by means of a screw bolt —6— is fastened the compression spring —7— (Fig. 1) or the tension spring —8— (Fig. 2). By this bolt —6— (Fig. 3) is regulated the tension of the spring. The ends of the tension spring —8— (Fig. 2) or of the compression spring —7— (Fig. 1) by means of the eyes —23— are connected to the rear wall —26— of the housing —10— and to the plate —22— of the screw bolt —6—. The joint 5 of the blade slides upon the slide plate —9— which forms also the bottom of the casing —10—, inside which is located the spring acting upon the said point. On the top the casing is closed by a detachable cover —11—.

The heel 12 of the blade 3 is beveled at —24— and by means of a pivot —20— hinged to a support —13— which by the screw bolt —15— is connected to a compression spring —14— (Fig. 4). The support —13— with the pivot of the blade slides upon the slide plate —9— of the casing —17— provided with a detachable cover —18—. Adjacent to the switch blade is a supporting beam —21—.

The working of the switch is the following: If a car running on the main track in the direction of the arrow —25— (Fig. 1) has reached the heel of the blade, it penetrates with the edge of the wheels in the notch 24 between the rail 1 and heel 12

of the blade, and pushes the blade back by overcoming the resistance of the spring 14. In this movement the blade 3 turns around its point as a center. The car by keeping on running, causes the blade to move backward, when it is in the position shown in Fig. 1, thus compelling the said blade to turn around its heel as a center. If, however, the car is moving in a direction opposite that indicated by the arrow—or in other words is moving to the right according to Fig. 1, and the point of the blade is standing away from the rail 1, as indicated in Fig. 2, the car wheels engage with the heel of the blade and move the latter away from the rail 1. As soon, however, as the car has passed the switch, the blade resumes its normal position.

My purpose in making the blade movable at the end provided with the heel is to enable the blade to be made shorter and consequently cheaper than would be the case if the blade turned upon a fixed pivot. In other words, by aid of my invention, a comparatively short blade can be employed for the reason that, being movable at the heel so as to turn out abruptly yet safely for the rolling stock, the necessity otherwise present for making the blade lengthy is effectively avoided.

Claims:

1. A railway switch comprising a main rail, a pivot for revolubly supporting the heel of the blade, a support for said pivot mounted to slide perpendicularly to the direction in which the rail extends, a movable casing for guiding the said support of said pivot, and a spring for pushing the heel of said blade against said main rail.

2. A switch of the class described comprising a main rail, a branch rail, a deviating blade, and means for allowing said blade to swing alternately upon the heel and upon the point.

3. In a switch of the class described, a slide plate, a blade loosely positioned on said slide plate, means arranged near each end of the blade for resiliently holding the blade in a predetermined position, and means arranged at the heel of said blade for pivotally connecting the blade to the means for holding the blade resiliently in a predetermined position.

4. In a switch of the class described, the combination with a rail, of a slide plate arranged on one side thereof, a blade loosely

mounted on said slide plate, means arranged near each end of said blade for resiliently pressing said blade against said rail, and means movable at right angles to the direction of said rail for pivotally mounting the heel of said blade, whereby the heel of said blade may move away from said rail.

5 In testimony whereof I affix my signa-

ture in the presence of two subscribing witnesses, in the city of Rome this 21st day of 10 March 1912.

MARIO GRIMALDI.
